UNITED STATES PATENT OFFICE

105,280

DESIGN FOR A COMBINED FURNITURE POST AND ARM

Harold H. Hines and George McKeown, Chicago, Ill., assignors to Pullman Couch Company, Chicago, Ill., a corporation of Illinois

Application May 22, 1937, Serial No. 69,484

Term of patent 3½ years

To all whom it may concern:

Be it known that we, Harold H. Hines and George McKeown, citizens of the United States, residing at Chicago, in the county of Cook and State of Illinois, have invented a new, original, and ornamental Design for a Combined Furniture Post and Arm, of which the following is a specification, reference being had to the accompanying drawing, forming part thereof.

Fig. 1 is a perspective view of a combined furniture post and arm showing our new design.

Fig. 2 is also a perspective view.

We claim:

The ornamental design for a combined furniture post and arm, as shown.

HAROLD H. HINES.
GEORGE McKEOWN.
